SITZ BATH

Charles F. Reavis, 1455 Norton St., Oroville, Calif.

Filed Aug. 31, 1959, Ser. No. 57,383

Term of patent 14 years

(Cl. D4—4)

Fig. 1.

Fig. 2.

Fig. 3.

Fig. 4.

Fig. 5.

Fig. 6.

FIG. 1 is a side elevational view of a sitz bath embodying my new design, the opposite side thereof being substantially the same;

FIG. 2 is a top plan view thereof;

FIG. 3 is an end elevational view thereof taken from the right of FIG. 1;

FIG. 4 is a bottom plan view thereof;

FIG. 5 is a top perspective view thereof taken from left of FIG. 1; and

FIG. 6 is a vertical sectional view taken on line 6—6 of FIG. 2.

I claim:
The ornamental design for a sitz bath, as shown and described.
